Primary Examiner—Ted Shooman*Assistant Examiner*—Adir Aronovich*Attorney, Agent, or Firm*—Jacox, Meckstroth & Jenkins**[57]****CLAIM**

The ornamental design of a flexible support stand for a camera or the like, as shown and described.

DESCRIPTION

FIG. 1 is a perspective view of a flexible support stand for a camera showing our new design;

FIG. 2 is a front view thereof;

FIG. 3 is a side view thereof;

FIG. 4 is the opposite side view thereof;

FIG. 5 is a rear view thereof;

FIG. 6 is a top view thereof; and,

FIG. 7 is a bottom view thereof.

The broken line showing of a camera is for illustrative purposes only and forms no part of the claimed design.
